UNITED STATES PATENT OFFICE.

JOHN W. MARSHALL, OF TIPTON, MISSOURI.

COLTER.

1,198,942.

Specification of Letters Patent. Patented Sept. 19, 1916.

Application filed April 24, 1916. Serial No. 93,261.

To all whom it may concern:

Be it known that I, JOHN W. MARSHALL, a citizen of the United States, residing at Tipton, in the county of Moniteau and State 5 of Missouri, have invented certain new and useful Improvements in Colters; and I do declare the following to be a full, clear, and exact description of the invention, such as will enable others skilled in the art to which 10 it appertains to make and use the same.

My invention which is an improved colter has for its object to provide a simple and efficient means for connecting the colter carrying arm to the usual shank which is 15 attached to the plow beam, said means serving to allow vertical adjustment of said arm without the use of nuts, set screws and the like.

With this general object in view, the invention resides in certain novel features of 20 construction and in unique arrangements of parts to be hereinafter fully described and claimed, the descriptive matter being supplemented by the accompanying drawing which 25 constitutes a part of this application, and in which:

Figure 1 is a side elevation of the improved colter applied; Fig. 2 is an enlarged vertical section through the head of 30 the colter carrying arm, showing more clearly its relation with its attaching shank; Fig. 3 is a vertical transverse section taken on the plane indicated by the line 3—3 of Fig. 2; and Fig. 4 is a horizontal section 35 taken on the plane of the line 4—4 of Fig. 2.

In specifically describing the construction shown in the drawing above briefly described, similar characters will be placed on corresponding parts throughout the several views and reference will be herein made 40 to the numerous elements by their respective indices. To this end, the numeral 1 designates a plow beam to which a colter attaching shank 2 is secured in any preferred manner, some type of clamp such as that designated at 3 being usually employed. The shank 2 or at least the lower end thereof stands upright and is received in a vertical bore 4 which is formed through an enlarged head 5 on the front end of a colter carrying arm 6, this arm being preferably bifurcated and having between its furcations any suitable type of colter 7. The

shaft 8 of the colter will preferably rotate with the latter in well lubricated bearings 55 in order that the device may run easily.

The wall of the bore 4 is formed with a plurality of vertically spaced circumferentially extending grooves 9 and with an upright groove 10 connecting them, the last 60 named groove necessarily opening through the upper end of the head 5 and preferably opening also through the lower end of said head in order to facilitate manufacture. The upright lower end of the shank 2 is 65 provided with a rigid laterally projecting stud 11 adapted for reception in any one of the grooves 9, whereby the head 5 may be adjusted vertically on the shank and held in adjusted position. Normally the stud 11 70 will be offset circumferentially from the vertical groove 10, but when the arm 6 is swung laterally, said stud and groove will be aligned in order that said arm may be shifted vertically to the desired extent. This 75 shifting will dispose one of the grooves 9 opposite the stud 11, whereupon when the arm 6 is swung rearwardly to its normal position, said stud will be received in this groove. Thus further vertical movement 80 of the arm 6 will be prevented until the plowman wishes to make further adjustments, these adjustments being obviously made for the purpose of forcing the colter 7 more or less into the earth. 85

By constructing the improved device in the manner shown and described, it will be obvious that the same may be easily and inexpensively manufactured and marketed, yet regardless of these advantages, the article will be highly efficient and durable and 90 will be extremely desirable due to the fact that no nuts or bolts need be loosened in order to adjust the colter vertically.

I claim:

In combination, an upright shank and a colter carrying arm having an upright bore receiving said shank, said bore having in its wall a plurality of vertically spaced circumferentially extending grooves and an 100 upright groove connecting them, said upright groove opening through the upper surface of the arm, the shank having a rigid laterally extending projection to be received in any one of the circumferentially extending 105 grooves to retain the arm in vertically

adjusted position on the shank, the upright groove being normally spaced circumferentially from said projection but being capable of alinement therewith to allow adjustment of the arm when the latter is turned upon the shank.

5 In testimony whereof I have hereunto set

my hand in presence of two subscribing witnesses.

JOHN W. MARSHALL.
